UNITED STATES PATENT OFFICE.

HARRY JAFFE, OF DETROIT, MICHIGAN, ASSIGNOR TO KALMAN STEEL COMPANY, OF CHICAGO, ILLINOIS, A CORPORATION OF DELAWARE.

AUTOMOBILE RADIATOR.

Application filed September 21, 1925. Serial No. 57,687.

My invention relates to improvements in automobile radiators and has special reference to cores, for such radiators, which cores have vertical water passages alternating 5 with air passages.

The object of my invention is to provide a radiator core which shall be constructed of vertically extending strips of thin sheet metal which extend from the top to the bottom thereof and which strips are formed to provide, between each two strips, forming a pair, a plurality of vertical water passages, and between adjacent pairs a vertically extending air passage opening through the front and back of the core and spacer parts formed out of said strips for spacing the pairs transversely of the core to form the air passages.

A further object of my invention is to provide a radiator core which shall simulate the well known fin and tube type of core the core consisting of vertically extending strips and the tubes being formed by such strips.

25 A further object of my invention is to provide a radiator core made up of a plurality of vertically extending elements each made of thin sheet metal only and each having a plurality of longitudinally extending tubular water passages and integral outwardly extending spacer formations adapted to contact with similar formations on adjacent elements for spacing the elements apart.

35 A further object of my invention is to provide a core of the fin and tube type made of vertically extending thin sheet metal strips and which shall have vertically extending water passages alternating with air passages the water passages having single thickness walls adapted to be contacted by water on the inside and air on the outside.

45 A further object of my invention is to provide a core of the fin and tube type which shall have heat radiating fins formed integrally with the walls of the tubes whereby the heat radiating capacity is greatly increased.

50 A further object of my invention is to provide a core of the fin and tube type which shall have tubes formed of metallic tubular parts extending from the top to the bottom of the core and heat radiating fins formed integrally with said tubular parts.

A further object of my invention is to provide a core of the fin and tube type which shall be made of a plurality of identically formed strips extending from top to bottom of the core and formed to provide a plurality of tubular vertical water passages between each two strips forming a pair and to provide partly severed and bent out spacer projections adapted to space the pairs apart to form air passages.

A further object of my invention is to provide a radiator simulating the honey-comb type and having rows of vertical tubular water passages alternating with air passages and made up of vertically extending thin sheet metal strips.

A further object of my invention is to provide a core of the honey-comb type which shall have tubes extending vertically through alternate vertical rows of the radiator air passages and heat radiating fins integral with the walls of the tubes extending into the air passages of the other vertical rows.

A further object of my invention is to provide an element for use in constructing radiator cores which element shall be made of sheet metal and shall provide a plurality of vertical water passages and a plurality of partly severed and outwardly formed heat radiating fins or projections.

A further object of my invention is to provide a sheet metal element for use in forming a core, the sheet metal formed to provide tubular water passages having single thickness walls and spacer parts integrally connected to said walls.

A further object of my invention is to provide a sheet metal element for use in forming a core, the sheet metal formed to provide tubular water passages having single thickness walls, and partly severed parts bent outwardly to form element spacers which serve to radiate heat.

Further objects, utilities and benefits will appear from the following description and accompanying drawings in which:—

Fig. 1, is a fragmentary front elevation of an automobile radiator embodying my invention;

Fig. 2, is a fragmentary vertical section on the line 2—2 of Fig. 1;

Figs. 3 and 4, are fragmentary vertical sections on the lines 3—3 and 4—4 respectively of Fig. 2;

Figs. 5 and 6, are fragmentary horizontal sections on the lines 5—5 and 6—6 respectively of Fig. 2;

Fig. 7, is a fragmentary perspective view of one end portion of one of the formed strips of which the core is made up;

Fig. 8, is a sectional view similar to Fig. 5 but showing only two adjacent strips slightly separated;

10 Fig. 9, is a sectional view similar to Fig. 6 but like Fig. 8, showing only two adjacent strips slightly separated; and

15 Fig. 10, is a sectional view similar to Fig. 5 and showing a slightly modified construction.

An automobile radiator of the kind to which my invention relates comprises a core 1 which is interposed between a top tank 2 and a bottom tank, not shown, and serves 20 to cool the water as the same flows down from the upper tank to the lower tank air flowing through the core from front to back, to carry away the heat.

The fin and tube type of radiator core to 25 which in a sense, my invention relates is ordinarily constructed of vertically extending tubes sealed at their ends into the top and bottom tanks and through which the water flows down as it is cooled, the tubes 30 being projected through a plurality of horizontally extending fin plates or strips which assist in dissipating the heat.

It goes without saying that for effective 35 and efficient radiation of the heat from the water in the tubes the tubes and the fin plates must be metallically connected where the tubes pass through the plates. This seems a difficult point to accomplish at a cost which is not prohibitive and many if 40 not all such radiators in use lack efficiency on account of looseness at these points:

The ordinary honey-comb core which the 45 radiator of my invention simulates in appearance consists either of vertical strips combined with vertical tubes or of vertical strips forming narrow elongated usually zig-zag passages alternating with spacer strips.

As distinguished from such forms of cores 50 the core of my invention consists of a plurality of vertically extending strips 3, which are all alike and out of which are formed both the water tubes and the spacers for holding the water tube elements apart and 55 forming the intervening air spaces.

As shown in the drawings each strip 3 which is made of very thin sheet metal is of a width to extend from front to back of the core. It is bent over at its ends to form 60 right angle lateral flanges 4 adapted to cooperate with similar flanges of the other strips to form a flat top and a flat bottom for the core, and turned back flanges 5 adapted to contact with flanges of adjacent 65 strips to form suitable connection between

these strips at their ends when the core is immersed in solder.

Each strip is formed between its ends to provide a plurality of half cylindrical depressions 6 extending from the top to the bottom of the formed strip and adapted, in conjunction with the similar half round longitudinal depressions or grooves in a similar strip to form vertical water passages 7. As shown these water passages are 70 circular in cross section this form serving the purpose best and best avoiding possibilities of clogging the radiator with sediment. The half cylindrical tubular parts or depressions are arranged symmetrically as to the 75 lateral edges of the strip so that all of the strips can be formed upon one die mechanism and when arranged face to face the half cylindrical depressions of one strip will 80 accurately register with the like depressions 85 in the other strip to form the water passages 7.

At each side of each depression 6 and running from end to end of the strip is a 90 narrow flat surface 8 which lies in the original plane of the strip and the similar flat surfaces of two strips when arranged face to face to form the water passages 7 will 95 contact with each other throughout their length and breadth thus providing joints 9 adapted to make the passages watertight from end to end when these surfaces are 100 properly soldered together as shown in Figs. 5 and 6.

When two strips are thus arranged face 105 to face they form what may be termed a radiator element providing a plurality of vertical water passages extending from end to end thereof. Such pairs of strips joined 110 to form elements having water passages and having the soldered connecting flanges 115 might be arranged to form a core but it would lack rigidity unless braced transversely and it would lack efficiency as there 120 would not be sufficient radiating surface.

To complete the core I form parts of each 125 sheet outwardly to provide spacer projections or parts 10 having flat contacting surfaces 11 at their outer ends parallel with the plane of the strip and adapted to contact with similar surfaces on adjacent strips for spacing the elements apart and when joined by solder for holding adjacent elements together. These projections are 130 formed up out of the flat parts 12 of the strips between the several half cylindrical grooves and out of the flat longitudinal edge portions 13 of the sheet I form similar contacting projections 14 having similar flat outer surfaces 15. The flat outer surfaces 11 and 15 are joined at their ends to the body 135 of the strips by inclined parts or walls 16 and 17 respectively and the parts are so proportioned and formed that when the strip is viewed edgewise the flat outer parts 140

11 and 15 with their inclined connecting parts 16 and 17 form respectively half hexagons and when the elements are assembled to form a core they give the core the 5 honey-comb appearance shown.

The spacer parts 10 and 14 not only serve to properly space the elements but by spacing the water passages apart they form air passages 18 extending from front to back 10 of the core and from top to bottom thereof although their ends are closed by the bent over flanges 4.

The spacer parts 10 and 14 also serve most effectively as heat radiating fins as they lie 15 directly in the passages 18 through which the air flows to cool the radiator. Furthermore the parts 12 and 13 out of which the spacer parts 10 and 14 are formed serve as heat radiating flanges or fins.

20 The parts 10 and 14 are formed out of the strips by severing them along the two lateral edges of the parts 11 and 16 in the one case and at the inner edges of the parts 15 and 17 in the other case as shown at 18, 18 and 19 respectively along lines longitudinal 25 of the strip or in other words parallel with the tube formations 6. Between these slits and the adjacent edges of the tube formations 6 are the flat contacting surfaces 8 which serve to seal the water passages along 30 the edges of the tube formations.

For the purpose of making the spacer formations more rigid I may form a small half round rib 20 extending centrally of 35 the parts 11 and 16 and from end to end of the spacer projection.

For cross connecting adjacent air passages 40 and to better solder the strips together I form the strips 3 with openings 21 through the flat parts 12 and vertically between the spacer parts 10. These holes not only allow the air to circulate crosswise between 45 the air passages but assist in soldering the strips together to form the elements as the solder can freely enter between the two strips of the element through these openings.

Having made enough of the single strips 50 I arrange them in pairs face to face to form the elements with the water passages and arrange enough of the elements side by side to form the core. Then I tightly clamp the parts together in a suitable clamping frame and immerse the whole in a bath of melted solder allowing the solder to flow through 55 all the tubes thus coating them inside as well as to cover every external surface. By this means I not only cover every part of external and internal surface with solder but I also permanently join the strips to 60 form the elements and the elements to form the core.

As shown in Fig. 10 I may make the 65 elements of a single strip instead of two strips. For this purpose I take a strip 22 twice as wide as the depth of the core from front

to back and I form this strip to produce the tubular and spacer formations of two single strips side by side, then I fold over one half of the strip upon the other half on the longitudinal median line 23 thus 70 bringing the tubular formations and the spacer formations into the same relation as heretofore described except that the spacer formations on the folded edge of the element are lacking. The line upon which this 75 double wide strip is folded is coincident with the outer edges of the adjacent flat surfaces 8 bordering the adjacent water passage grooves 6.

In producing this form each operation 80 of the die mechanism forms a strip for a complete element and thereby the cost is reduced.

It is to be noted that the water is in contact with the inner surface of the wall of 85 the tube and that the air is in contact with the outer surface of the same single thickness wall. Furthermore that every heat radiating part of the core is not only metallically connected or joined to the water carrying part but is integrally formed therewith. Any soldered or other joint through which heat must travel in being dissipated from the water walls is more or less of a hindrance to the free flow of heat along such 90 path and cuts down the efficiency of the radiator. By means of my invention I am enabled to provide a radiator of absolutely minimum weight and with 100 percent efficiency as there are no joints soldered or 100 otherwise across which the heat must flow to escape.

As many modifications of my invention will readily suggest themselves to one skilled 105 in the art I do not limit or confine my invention to the specific details of construction and arrangement of parts herein shown and described.

I claim:—

1. A radiator core comprising a plurality 110 of vertically extending strips, the body portions of the strips being flat and extending in single thickness from the top to the bottom of the core, the strips having longitudinally extending grooves adapted to cooperate to form vertically extending water passages in the core, portions of the strips partly severed and formed out of the planes of the strips the formed-out portions of adjacent strips contacting to space the water 115 passages apart transversely of the core.

2. A radiator core comprising a plurality 120 of vertically extending strips, each strip provided with a plurality of longitudinal grooves adapted to cooperate with other strips to form vertically extending water 125 passages in the core, each strip being equal in width to the thickness of the core from front to back, the grooves in each strip bordered by flat portions of the strip ex- 130

tending from end to end, such portions of two cooperating strips adapted to be soldered face to face to seal the water passages, portions of the strips between the several 5 grooves and portions of the edge parts of the strips being partly severed and formed outwardly and adapted to contact with and be soldered to like formed parts of other strips to space the water passages apart from 10 side to side of the core.

3. An element for use in conjunction with other similar elements for making a radiator core, said element made up of two strips of sheet metal, the body portion of each strip 15 being flat and extending in single thickness from end to end of the element, each strip being formed with longitudinal grooves adapted to cooperate with the grooves of a co-operating strip to provide continuous 20 water passages through the element, and portions of the sheet metal partly severed and formed outwardly to provide means for spacing the water passages apart when the element is combined with other similar 25 elements to make up a core.

4. An element for use in conjunction with other similar elements for making a radiator core, said element made up of two strips of sheet metal, the body portion of each strip 30 being flat and extending in single thickness from end to end of the element, each strip being formed with longitudinal grooves adapted to cooperate with the grooves of a co-operating strip to provide continuous 35 water passages through the element, and portions of the sheet metal partly severed and formed outwardly to provide means for spacing the water passages apart when the element is combined with other similar 40 elements to make up a core, the production of said outwardly formed portions providing openings extending from side to side of the element.

5. An element for use in conjunction with 45 other similar elements for making a radiator core, said element made up of two strips of sheet metal, the body portion of each strip

being flat and extending in single thickness from end to end of the element, each strip being formed with longitudinal grooves 50 adapted to provide continuous water passages through the element, and portions of the sheet metal partly severed and formed outwardly to provide means for spacing the water passages apart when the element is combined with other similar elements to make up a core, the production of said formed out portions providing the element with openings extending from side to side thereof, and the element provided with other 60 openings between the water passages and extending from side to side of the element.

6. A radiator core built up of a plurality of strips of thin sheet metal, the body portion of each strip being flat and extending 65 in a single thickness from the top to the bottom of the core, each strip being provided with longitudinal grooves adapted to cooperate with similar grooves in an adjacent strip to form vertical water passages in the 70 core, portions of the strips being partly severed and formed outwardly, the formed-out portions being adapted to space the water passages apart from side to side of the 75 core, the said flat portions of cooperating strips adapted to be soldered together to seal the water passages.

7. A radiator core comprising in combination a plurality of elements each element being composed of two strips of metal, each 80 strip having a plurality of spaced continuous, longitudinal, half-round grooves formed therein, the flat portions of two strips being adapted to be brought into contact and soldered to form a plurality of vertically extending water passages, the flat portions of the strips intermediate the groove being slotted, the slotted portions formed laterally outwardly to act as spacing 85 means for an adjacent element.

In testimony whereof, I have hereunto set my hand, this 21st day of July, 1924.

HARRY JAFFE.
